UNITED STATES PATENT OFFICE.

GODFREY R. DAMIANI, OF CHICAGO, ILLINOIS.

DOOR SILENCER.

Application filed October 31, 1921. Serial No. 511,691.

To all whom it may concern:

Be it known that I, GODFREY R. DAMIANI, a citizen of the United States, and resident of Chicago, in the county of Cook and State 5 of Illinois, have invented a certain new and useful Improvement in Door Silencers, of which the following is a full, clear, concise, and exact description, reference being had to the accompanying drawings, forming a part 10 of this specification.

My invention relates to door silencers, and has for its principal object the provision of a device of this kind which will effectively eliminate rattling and other noises incident 15 to the closing or opening of a door.

Another object is to provide a door silencer that is substantially concealed when the door is closed.

It is also an object of my invention to 20 provide a door silencer that may be economically produced and readily applied to any standard door.

The foregoing and other objects, as well 25 as the construction of the several parts of a preferred embodiment of my invention, will be made apparent by reference to the following specification and accompanying drawings, in which—

Figure 1 is a view in elevation of those 30 parts of the device which are secured to the door frame;

Figure 2 is a sectional view taken on the line 2—2 of Figure 1 looking in the direction indicated by the arrows;

Figure 3 is a sectional view of one of the 35 parts of my door silencer, this view being taken on the line 3—3 of Figure 2;

Figure 4 is a view in elevation, showing the several parts of the device in position 40 upon a door and its frame, the door being closed;

Figure 5 is a view, partly in section and 45 partly in elevation, illustrating certain elements of the silencer in the positions assumed thereby when the door is closed;

Figures 6, 7 and 8 are detail views in 50 perspective of parts of the mechanism shown in assembly in Figure 5;

Figures 9, 10 and 11 are detail views in 55 perspective of parts of the mechanism shown in assembly in Figure 3.

In the drawing, 9 indicates a door hung within a door frame 10 and adapted to abut the usual stop strip 11. Secured to the door 60 by means of the screws 12 is a pad of rubber or equivalent compressible material 13. The

door frame is recessed at 14 for the reception of a plate 15 of channel shape, having parallel flanges 16 and 17. The plate 15 is secured to the door frame by means of screws 18—18 extending through the apertures 19—19 in the plate. As best shown in Figures 1 and 6, the plate 15 is adapted to pivotally support a pair of bell crank levers 20—20 which are mounted on the plate 65 15 by means of rivets 21—21 extending through the portions 22 of the levers 20—20. The flanges 16 and 17 are provided with studs 24 and 25 and the levers 20—20 are provided with studs 26 and 27. Between 70 the studs 24 and 26 and the studs 25 and 27 are disposed springs 28—28 tending to force the levers 20—20 toward each other. To limit the movement of the levers 20—20, the plate 15 carries stops 29—29 which engage 75 the portions 22 of the levers 20—20, as best illustrated in Figure 1. As the door is closed, the resilient pad 13 enters between the faces of the levers 20—20 and the closing of the door is impeded by reason of the 80 vertical pressure exerted on the pad 13 by the levers 20—20. As indicated in Figure 1, the receiving faces of the levers 20—20 are formed to permit the reception of the pad 13, and the distance between the receiving 85 faces of the levers is substantially the same as the width of the pad 13, so that, when the door is opened and the pad 13 removed from between the levers 20—20, the levers will have been brought into engagement with the 90 stops 29—29 gradually.

I prefer to have the pad 13 slightly tapered, being narrower at the portion of the pad last to leave the engaging faces of the levers 20—20 when the door is opened. 95 This avoids the noise that would result from having the pad 13 of a width greater than the distance between the engaging faces of the levers.

Mounted in alignment with the stop strip 100 11, and held to the door frame 10 by screws 30—30, is a support 31 having a wall 33. Extending through the aperture 34 of the support 31 is a guide pin 35 threaded at 105 36 and having a head 37. The guide pin 35 has threaded engagement with and is secured to a slidable plate 38 which carries a rubber or other resilient pad 39. The rubber pad may be secured to the slidable plate 38 by means of screws extending through the 110 apertures 40—40. The slidable plate 38 carries therewith a pin 41 which is arranged

to extend through the slot 42 in the wall 33. A helical compression spring 43 extends between the support 31 and a nut 44 abutting the slidable plate 38. The pin 35 being slidably mounted in the aperture 34 of the support 31, the rubber pad 39 will, therefore, be movable inwardly against the tension of the spring 43. Disposed between the head 37 and the support 31 is a cushioning washer 45 which is intended to permit the spring 43 to operate the slidable parts without noise.

From the foregoing description, and by reference to the drawings, it will be apparent that, on closing the door, the rubber pad 13 enters between the faces of the levers 20-20. The pressure exerted on the pad 13 or the spring pressed levers checks the travel of the door until the door and pad 13 engage the yielding pad 39 which moves against the tension of the spring 43 to permit closing of the door. When the door is in closed position, the same is prevented from rattling by the pressure exerted on the pad 13 by the spring pressed levers 20-20.

25. What I claim is:

1. In combination with a door, a door frame, a silencer comprising a resilient pad attached to the door, a plate attached to the door frame, a pair of levers pivoted to said plate, spring means arranged to move said levers toward each other, stops to limit the movement of said levers, said levers being formed to receive between them the resilient pad carried by the door, the distance between the receiving faces of the levers being substantially equal to the width of the portion of the pad arranged first to engage the levers, a yielding member comprising a support carried by the frame, a slidable plate provided with a resilient member, said slidable plate having pin and slot connection with the support, a guide pin extending through the base of said support and secured to the slidable plate, spring means disposed between the slidable plate and the support, said guide pin provided with a head disposed on the opposite side of the support, and a resilient member between the pad and the support.

50. 2. In combination with a door, a door frame, a silencer comprising a resilient pad attached to the door, a plate attached to the door frame, a pair of levers pivoted to said plate, spring means arranged to move said levers toward each other, said levers being formed to receive between them the resilient pad carried by the door, the distance between the receiving faces of the levers being substantially equal to the width of the portion of the pad arranged first to engage the levers, a yielding member comprising a support carried by the frame, a slidable plate provided with a resilient member, said slid- 65 able plate having pin and slot connection with the support, a guide pin extending

through the base of said support and secured to the slidable plate, spring means disposed between the slidable plate and the support, said guide pin provided with a head disposed on the opposite side of the support, and a resilient member between the pad and the support.

3. In combination with a door, a door frame, a silencer comprising a resilient pad attached to the door, a plate attached to the door frame, a pair of levers pivoted to said plate, spring means arranged to move said levers toward each other, stops to limit the movement of said levers, said levers being formed to receive between them the resilient pad carried by the door, the distance between the receiving faces of the levers being substantially equal to the width of the portion of the pad arranged first to engage the levers, a yielding member comprising a support carried by the frame, a slidable plate, said slidable plate having pin and slot connection with the support, a guide pin extending through the base of said support and secured to the slidable plate, spring means disposed between the slidable plate and the support, said guide pin provided with a head disposed on the opposite side of the support, and a resilient member between the pad and the support.

4. In combination with a door, a door frame, a silencer comprising a resilient pad attached to the door, a plate attached to the door frame, a pair of levers pivoted to said plate, spring means arranged to move said levers toward each other, stops to limit the movement of said levers, said levers being formed to receive between them the resilient pad carried by the door, the distance between the receiving faces of the levers being substantially equal to the width of the portion of the pad arranged first to engage the levers, a yielding member comprising a support carried by the frame, a slidable plate provided with a resilient member, said slid- 110 able plate having pin and slot connection with the support, a guide pin extending through the base of said support and secured to the slidable plate, and spring means disposed between the slidable plate and the support.

5. In combination with a door, a door frame, a silencer comprising a resilient pad attached to the door, a plate attached to the door frame, a pair of levers pivoted to said plate, spring means arranged to move said levers toward each other, said levers being formed to receive between them the resilient pad carried by the door, a yielding member comprising a support carried by the frame, a slidable plate provided with a resilient member, said slidable plate having pin and slot connection with the support, a guide pin extending through the base of said support and secured to the slidable plate, and spring 130

means disposed between the slidable plate and the support, said guide pin provided with a head disposed on the opposite side of the support.

5 6. In combination with a door, a door frame, a silencer comprising a resilient member, a yieldable member arranged to engage the resilient member, a support on the frame, and a yieldable abutment slidably mounted 10 in said support and having pin and slot connection therewith.

7. In combination with a door, a door frame, a silencer comprising a resilient member, a yieldable member arranged to engage 15 the resilient member, a support on the frame, a guide member extending through the support and having attached thereto a slidable member, and spring means between said support and slidable member, said slidable member having a pin extending therefrom and co-operating with a slot in the support.

8. In combination with a door, a door frame, a silencer comprising a support, a guide member extending through the support and having attached thereto a slidable member, and spring means between said support and the slidable member, said slidable member having a pin extending therefrom and co-operating with a slot in the support. 25

0 9. A door silencer comprising a resilient member, a support, a pair of levers pivotally mounted on the support, said levers having broad engagement faces to receive the resili- 0

ent member, and spring means yieldingly to hold the levers in engagement with the resilient member when the door is in closed position.

10. A door silencer comprising a resilient member carried by the door, a support carried by the door frame, a pair of levers pivotally mounted on the support, said levers being provided with engagement faces to receive the resilient member, the distance between the receiving faces of the levers being substantially equal to the width of the 40 resilient member, and spring means adapted yieldingly to present the engaging faces of the levers to the resilient member. 45

11. A door silencer comprising a resilient member, a channel-shaped support carried 50 by the frame, a pair of levers pivoted to the support, said levers being provided with broad engagement faces, lugs carried by said levers and the flanges of the channel-shaped support, and spring means disposed 55 between the levers and the channel-shaped support and positioned by said lugs yieldingly to present the levers to the resilient member.

In witness whereof, I hereunto subscribe 60 my name this 28th day of October, 1921.

GODFREY R. DAMIANI.
